DESIGN FOR A NUT ROASTING MACHINE

Ernest W. Bly and Harry H. Lutzy,
Cleveland, Ohio

Application November 19, 1934, Serial No. 54,084

Term of patent 14 years

To all whom it may concern:

Be it known that we, Ernest W. Bly and Harry H. Lutzy, citizens of the United States, residing at Cleveland, in the county of Cuyahoga and State of Ohio, have invented a new, original, and ornamental Design for a Nut Roasting Machine, of which the following is a specification, reference being had to the accompanying drawing, forming a part thereof, in which—

Figure 1 is a perspective view of a nut roasting machine, showing our design.

Figure 2 is a perspective view similar to Figure 1, but showing the drum in discharging position.

We claim:

The ornamental design for a nut roasting machine, substantially as shown and described.

ERNEST W. BLY.
HARRY H. LUTZY.
